US0D1075985S

(12) **United States Design Patent** (10) **Patent No.:** **US D1,075,985 S**
(45) **Date of Patent:** **** May 20, 2025**

(54) **DIVOT TOOL**

- (71) Applicant: **TUMI, INC.**, Edison, NJ (US)
(72) Inventors: **Peter Chang-lin Wu**, Great Neck, NY (US); **Victor G. Sanz**, Whitehouse Station, NJ (US)
(73) Assignee: **TUMI, INC.**, Edison, NJ (US)
(**) Term: **15 Years**
(21) Appl. No.: **29/978,021**
(22) Filed: **Dec. 11, 2024**

(57) **CLAIM**

The ornamental design for a divot tool, as shown and described.

DESCRIPTION

FIG. 1 is a front perspective view of the divot tool in a first condition;

FIG. 2 is a front view of the divot tool of FIG. 1;

FIG. 3 is a rear view of the divot tool of FIG. 1;

FIG. 4 is a right side view of the divot tool of FIG. 1;

FIG. 5 is a left side view of the divot tool of FIG. 1;

FIG. 6 is a top view of the divot tool of FIG. 1;

FIG. 7 is a bottom view of the divot tool of FIG. 1;

FIG. 8 is a front perspective view of the divot tool of FIG. 1 in a second condition;

FIG. 9 is a front view of the divot tool of FIG. 1 in the second condition; and,

FIG. 10 is a rear view of the divot tool of FIG. 1 in the second condition.

The broken lines shown in the figures illustrate portions of the divot tool that form no part of the claimed design. The broken line circle in FIG. 10 is a graphic line only and forms no part of the claimed design. The drawings include surface shading that represents contour and not surface ornamentation.

1 Claim, 7 Drawing Sheets
